UNITED STATES PATENT OFFICE.

THOMAS R. MCKENNAN, OF EAST PALESTINE, OHIO.

DESIGN FOR A TIRE-CASING.

47,139.

Specification for Design.

Patented Mar. 23, 1915.

Application filed November 12, 1914. Serial No. 871,796. Term of patent 7 years.

To all whom it may concern:

Be it known that I, THOMAS R. MCKENNAN, a citizen of the United States, residing at East Palestine, in the county of Columbiana and State of Ohio, have invented a new, original, and ornamental Design for Tire-Casings, of which the following is a specification, reference being had to the accompanying drawing, forming part thereof.

The figure is a plan view of a portion of a tire casing, showing my new design.

I claim:—

The ornamental design for a tire casing, as shown.

THOMAS R. MCKENNAN.

Witnesses:

R. Y. STEVENSON,
R. B. TAGGART.
